UNITED STATES PATENT OFFICE.

DOMINICK CASWELL, OF WATERTOWN, NEW YORK.

OIL BURNER.

Application filed March 7, 1927. Serial No. 173,393.

This invention relates to an oil burner, designed particularly for use in connection with house furnaces, stoves, steam generators, and other cooking and heating apparatus, and has for its object to provide a simplified type of liquid fuel burner, which may be readily and quickly applied to the fire-grate of an ordinary heating apparatus, and which operates by gravity feed, and 10 burns the fuel without any waste or odor.

A particular object of the invention is to provide a novel construction and arrangement of the combustion chamber of the burner, whereby the objectionable noise is 15 eliminated, and whereby all danger of accumulation of soot or burnt carbon, which impairs the operation of this type of burner in common use, is entirely obviated. A further object is to provide a novel fresh air 20 manifold which discharges the air directly above and concentric to the fuel nozzle or jet, the discharge end of said manifold being so positioned relatively to the plane of combustion as to preheat the air before it enters 25 the combustion chamber. A further object is to provide a novel fuel nozzle, which is arranged to spread the flame as it rises in all directions radially, the said nozzle also being arranged to similarly spread the de- 30 scending air in a manner to effect a union of said elements about midway between ends of the nozzle. A further object is to provide means for effecting a slight continuous feed of the liquid fuel, for maintaining a constant 35 pilot flame, while the burner is normally shut-off, the said nozzle being equipped with a valve which opens by the pressure of the fuel when the burner is being operated at full capacity, the said valve closing by 40 gravity when the feed of the fuel is reduced by a thermostat, or other control.

The various features and parts of the invention will be understood from the detailed description which follows, and by references 45 to the accompanying drawings, in which:—

Figure 1 is a top plan view of the complete burner. Fig. 2 is a side elevation of the same. Fig. 3 is a central vertical longitudinal section, taken on line 3—3 of Fig. 50 1, showing the fuel valve in position for effecting the minimum feed of the fuel to the combustion chamber. Fig. 4 is a reduced top plan view of the base of the burner. Fig. 5 is a side elevation of the 55 same, showing the means for supporting the burner. Fig. 6 is a reduced side elevation

of the manifold and the integral hopper-like heat deflector. And Fig. 7 is a view showing a number of interfitting deflecting members that are disposed between the base and the manifold, the top and bottom rings in said view being interchangeable for varying the capacity of the burner.

In the drawings, 2 represents a hollow pan-like base, preferably circular, and having its top formed with a projecting annular flange 2'. At one side of the body 2 a flange portion 2^a extends handle-like beyond the body, the said extension being perforated. At intervals around the top of the base 2 integral lugs or ears, as 3, project laterally. These lugs are preferably formed with threaded sockets 3', to receive the top ends of legs or feet 3^a, by which the burner may be supported upon a grate or other part. The bottom of the base 2 is formed with a central threaded opening 2^b, in which may be inserted a fuel pipe 4, inside the base the perforation 2^b is surrounded by a concentric boss 2^c, and a number of concentric shallow depressions or grooves as 2^d, the latter being provided for distributing and retaining the liquid fuel during the operation of the burner. The fuel supplied by pipe 4 discharges directly into a nozzle 5, which is bored out axially for providing a passage 5' for the fuel, the bottom end of said nozzle being threaded for attachment to the pipe 4. The nozzle 5 is preferably conical, being shaped like a spinning top, whose narrow bottom seats upon the boss 2^c. The fuel delivered to the nozzle wells upwardly in the passage 5', and in case the feed of the fuel is of sufficient volume, the oil overflows the top end of the nozzle and gravitates toward the smaller groove 2^d. The top end of the fuel passage 5' is preferably normally closed by a valve 6, which consists of a cylindrical body 6' of less diameter than the bore 5', which is disposed in the said bore and a relatively large circular head 6^a, which rests upon the top of the nozzle, as best seen in Fig. 3. The nozzle is also provided with a number of small radial ducts, as 5^a, which are preferably disposed at an angle to the horizontal and tend to discharge small quantities of the liquid fuel downwardly into the nearest circular depression 2^d. The ducts 5^a are preferably relatively small and are employed mainly for supplying the small amount of fuel necessary to maintain a pilot flame, within the combustion chamber, when

the furnace is being operated at its lowest capacity, or when the fuel regulator (not shown) shuts down the burner, at which times the pressure of the fuel is less than is required to lift the valve 6. In practice, when the burner is being operated at full capacity, the valve 6 opens and closes at varying intervals owing to whether or not the feed of the oil is constant. This pulsating action of the valve prevents a continuous flow of the oil, which in a short time would effect the flooding of the pan 2, and interfere with the proper gasifying and combustion of the fuel. In other words, such flooding would tend to effect a "dirty" fire, that would give off considerable unconsumed carbon, impair the efficiency of the burner and waste the fuel.

7 represents the air manifold, which comprises a single arched pipe or tube, the receiving end of which is provided with a flange 7' that rests upon the extension 2^a, to which the manifold may be secured by bolts 7^a. Ordinarily the manifold retains its position without the bolts. Below the flange 2^a is connected a cold air conduit 8, which may conduct the air from out-of-doors, or from the room where the burner is located. The discharge end 7^b of the manifold is preferably positioned concentrically above the nozzle 5 (see Fig. 3), and this end is preferably formed with radial baffles or walls 7^c (see Figs. 1 and 3), which tend to break up the volume of the air into a number of streams and obviate the tendency of the main stream to discharge at one side of the manifold. The discharge end 7^b is usually disposed some distance above the top of the nozzle 5, and preferably above the plane of the flange 2' of the base, so as to provide suitable combustion space, as indicated at A, in Fig. 3. The manifold 7 is formed with a hollow inverted conical heat deflector 7^d, which may be cast with the tubular portion 7, and by means of which the heat rising from the combustion chamber A is deflected and spread in a well-known manner. The conical deflector 7^d preferably surrounds the free end of the manifold 7 and tends to preheat the air before it reaches the chamber A. In order to properly control the combustion and the disposition of the heat, I provide a number of ring-like deflecting members, as 9 and 10: The ring 9 is substantially flat and adapted to rest upon the flange 2' of the base and has an annular depending portion 9', which fits into the open top of the base, the said portion preferably being formed with an upward and inward tapering or deflecting surface 9^a, which directs the products of combustion towards the plane of the top of said ring and towards the manifold. The ring 10 is mounted upon the ring 9, and is detachably secured thereto by means of dowels 10' (see

Figs. 3 and 7). This ring has a sheer opening substantially the diameter of the opening in the ring 9, and is formed with an upward and outward tapering surface 10^a, which substantially parallels the taper of the conical deflector 7^d. This provides an annular discharge opening B of sufficient capacity to supply suitable heat for a furnace or other apparatus. 10^c represents a similar ring which may be substituted for the ring 10, in which the opening 10^d for the escape of the products of combustion from the chamber A is considerably reduced. The ring 10^c may be substituted for the ring 10 in case it is desired to reduce the capacity of the burner.

Obviously my burner may be employed independently of a furnace like any of the portable oil burners for heating one or more rooms.

The bottom of the base 2 is formed with a number of radial baffle ribs as 12, which prevent circular or whirling currents in the combustion chamber A. In case of accidental flooding of the base 2, the surplus fuel may escape through a port 13 (see Fig. 3).

In practice the nozzle 5 becomes hot and when the fuel feeding and regulating parts are properly adjusted, the fuel becomes converted into gas, and very little of the liquid reaches the collecting grooves 2^d.

Having thus described my invention, what I claim, is—

1. An oil burner comprising a base having a normally open top, an air conduit supported by the base, its free end disposed above and adapted to discharge the air toward the center of the base, said conduit being arranged with a frusto-conical portion adapted to spread the products of combustion rising from the base, a cover for the base having a flaring portion arranged parallel to the tapered wall of the frusto-conical portion to provide an annular outlet for the heat, a mixing member rigid to the bottom of the base having an oil passage pointing towards the discharge end of the conduit, an oil pipe protruding through the bottom of the base and threaded into the mixer member, and a gravitational valve for controlling the flow of the oil from said passage.

2. An oil burner comprising a hollow base having an open top formed with a radial arm, the bottom of said base having an opening to admit an oil pipe, a nozzle mounted on said pipe inside of the base, said nozzle being double cone-shaped and having a passage aligning with the bore of said pipe, said nozzle having radial ports that direct small jets of the oil downwardly towards the bottom of the base, a gravitational valve controlling the flow of the oil from said passage, an air conduit supported by said arm

and extending inwardly and discharging the air downwardly towards said nozzle, said conduit being formed with an inverted cone-shaped heat deflecting ring disposed between 5 the conduit and the base and cooperating with the inverted conical deflector for spreading the heat rising from the base.

3. An oil burner comprising a hollow base having a normally open top and a central 10 opening in its bottom to admit an oil pipe, a mixing member supported by the bottom of the base and being rigid with said pipe, a valve controlling the flow of the oil from the top of the said mixer, said mixer formed 15 with radial ports that discharge small jets of oil towards the bottom of the base, an annular member partially closing the top of said base formed with oppositely facing angular deflecting surfaces, and an air conduit 20 supported at one side of the base and arching the adjacent portion of the base and said annular member, the free end of said conduit disposed above and concentric to the mixer and said annular member and dis- 25 charging the air downwardly towards the mixer, said conduit being formed with an inverted conical deflecting portion arranged concentric to the annular member to provide an annular outlet for the products of com- 30 bustion generated within said base.

4. An oil burner comprising a hollow base having an open top and a closed bottom, and having a radial arm, an oil pipe disposed centrally in the bottom of the base, 35 a fuel nozzle mounted on said pipe having a passage to discharge the oil upwardly towards the top of the base, a gravitational valve controlling the discharge of the oil from said nozzle while the burner is operating, said nozzle being formed with small oil 40 ports for maintaining a pilot flame when the burner is shut down, an air conduit supported by said arm and arching the adjacent portion of the base, the free end of the said 45 conduit being disposed above and concentric to the nozzle, said conduit being formed with a conical deflector partially closing the top of the base and having flaring walls cooper- 50 ating with said nozzle for spreading products of combustion rising from said base.

5. An oil burner comprising a circular hollow body having an open top and a closed

bottom and having an arm in the plane of said top, an annular member partially closing the top of the body, said member being formed with oppositely facing angular deflecting surfaces that control heat rising from the body, an air conduit supported by said arm and arching the adjacent portion of the body, the free end of said conduit disposed above and concentric to said annular member and arranged to discharge the air downwardly towards the center of the base, an oil pipe piercing the bottom of the body concentric to the free end of the conduit, a 60 conical mixing member supported by said pipe and rigid with the bottom of the pipe, said mixing member having an oil passage aligning with the bore of the pipe and having a plurality of radial ports to discharge 65 small jets of oil for maintaining a pilot flame when the burner is shut down, and a gravitational valve controlling the discharge of the oil from the top of said mixing member. 70

6. An oil burner comprising a hollow circular base having an open top and a closed bottom, the latter having a central opening to admit an oil pipe, a double cone-shaped mixing member mounted on said pipe at the 75 bottom of the base, said member having a vertical oil passage, and having radial ports tapping said passage for directing small jets of the oil towards the bottom of the base, a gravitational valve normally closing the upper end of said passage and controlling the discharge of the oil when the burner is being operated, an annular member partially closing the top of the base having flaring deflecting surfaces, an air manifold supported 80 at one side of the base, said manifold being arched, and its free end being disposed above and concentric to said annular member adapted to discharge the air downwardly to mingle with the flame surrounding said mixing member, said manifold being formed with flaring walls arranged concentric to and spaced from the flared walls of the annular member for providing a discharge opening 85 encircling said free end and preheating the 90 air flowing through the manifold. 95

In testimony whereof I affix my signature.

DOMINICK CASWELL.
